TARGET APPARATUS

Paul F. Gaus, Chicago, Ill.

Application May 23, 1934, Serial No. 727,031

8 Claims. (Cl. 273—102)

This invention relates to an amusement apparatus.

It is an object of this invention to provide an improved amusement apparatus which is relatively simple and inexpensive in construction and efficient in use.

Another object of this invention is to provide a novel amusement apparatus that is particularly intended for use in outdoor amusement parks, fairs, and the like.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a perspective view illustrating the invention assembled in position for use;

Fig. 2 is a top plan view, partly in section;

Fig. 3 is a fragmentary detail plan view;

Fig. 4 is a side elevational view of a target and latch mechanism embodied in the invention;

Fig. 5 is a side elevational view of the latch mechanism shown in Fig. 4.

Fig. 6 is a sectional detail view of the means for mounting the animal character embodied in the invention;

Fig. 7 is a fragmentary side elevational view of the means for mounting the animal character;

Fig. 8 is a part elevational view of the new apparatus in assembled position;

Fig. 9 is a vertical sectional detail view on line 9—9 in Fig. 8;

Fig. 10 is a horizontal sectional view on line 10—10 in Fig. 8;

Fig. 11 is a horizontal sectional detail view;

Fig. 12 is a sectional view on line 12—12 in Fig. 10;

Fig. 13 is a vertical sectional view on line 13—13 in Fig. 8;

Fig. 14 is a sectional detail view on line 14—14 in Fig. 8;

Fig. 15 is a sectional detail view on line 15—15 in Fig. 3; and Fig. 16 is a side elevational view on line 16—16 in Fig. 15.

A preferred form of the new amusement apparatus is shown in the accompanying drawings and therein the same is shown in conjunction with a fair or amusement park or other like amusement place, in which is provided a water pool 20. Arranged in this pool 20 is an animal character which is generally indicated at 21, and projecting upwardly from the pool 20 is a group of posts 22 which are ornamented to resemble trees, so

that the whole is given the appearance of the natural habitat of the animal simulated by the character 21.

Also projecting upwardly from the pool 20 is a vertical rod 23 which carries at its upper end a target 24. Rotatably mounted upon one of the posts 22, by means of suitable bearing blocks 26, (Fig. 8) is a horizontal shaft 25 (Figs. 8 and 12) which supports a seat or platform, generally indicated at 27; the seat 27 being fixedly attached or keyed to the shaft 25 so as to turn or rotate therewith (Fig. 12).

In the use of the new amusement apparatus, a boy sits upon the platform 27, above the level of the water in the pool 20, and the player throws a ball or like missile at the target 24. If the player succeeds in striking the target 24, means, presently to be described, are actuated to release the seat 27 and drop the boy therefrom into the pool 20, while at the same time this motion of the target 24, when struck, actuates means, also presently to be described, by which the animal character 21 is caused to move in the pool 20 toward the boy dropped therewith from the seat 27 by the act of the player in striking the target 24. After this operation, the boy climbs up out of the pool 20 by means of a ladder 28 (Fig. 8), and this climbing operation of the boy upon the ladder 28 operates means, presently to be described, by which the seat 27 is reset into horizontal position and the target 24 and animal character 21 are returned to or reset into their initial positions.

Having thus given a general description of the operation of the new amusement apparatus, a detailed description of the construction and operation of the same will now be given.

The seat structure 27 includes a horizontally projecting portion or platform 29, and it also includes a pair of blocks or bearing portions 30 which are arranged at opposite sides thereof (Figs. 8 and 10) and by which the seat is mounted upon its supporting shaft 25; the body or platform portion 29 of the seat 27 being pivotally mounted on the blocks 30 by means of a transverse horizontal shaft 31; and the inner or rear end portion of the seat platform 29 having a flat shock absorbing or buffer spring 32 arranged therebelow with its end portions projected into recesses 33 formed in the end blocks 30; the tension of the spring 32 and the amount of movement allowed the inner end portion of the seat platform 29 upon its pivot 31 being capable of variation by adjustment of set screws 34 and 55

35 which are mounted in the end blocks 30 (Fig. 12).

Carried by the horizontal shaft 25 is a beveled gear 36 (Fig. 8) which meshes with a corresponding beveled gear 37, the gear 37 being carried by a vertical shaft 38. This shaft 38 is rotatably mounted in a vertically extending channel 39 (Figs. 8 and 11) which is formed in the supporting post 22.

10 At its lower end the vertical shaft 38 carries a beveled gear 40 (Fig. 8) which meshes with a corresponding beveled gear 41, the gear 41 being mounted upon one end portion of a horizontal shaft 42 which is submerged in the pool 20. One 15 end of the shaft 42 is mounted upon the post 22 (Fig. 8) and the other end thereof is mounted upon a supporting frame 43 which is also submerged in the pool 20.

At its other end the horizontal shaft 42 carries a beveled gear 44 (Fig. 2) which meshes with a corresponding beveled gear 45, the gear 45 being carried by a second horizontal shaft 46 which is also rotatably mounted upon the supporting frame 43 and submerged in the pool 20.

20 Carried by the shaft 46 at one side of the supporting frame 43 is a counterweighted Y-shaped member, generally indicated at 47 (Fig. 2). This member 47 includes a counterweighted arm portion 48 and a pair of diverging arms 49 (Fig. 2).

25 Extending transversely between the upper end portions of the arms 49 is a shaft 50 and pivotally mounted on this shaft 50 is a frame, generally indicated at 51, which supports the body and upper jaw portions 57 and 76 (Fig. 8) of the animal character 21; the animal character 21 having a lower jaw portion 52 which is also pivotally mounted upon the shaft 50 by means of a sleeve 83 (Fig. 6); the lower jaw portion 52 of the animal character being urged toward the upper jaw portion 76 of the same and kept in a substantially horizontal position by means of coil springs 53 (Figs. 6 and 7), each of which has an end portion 54 that is attached to the lower jaw portion 52 of the animal character 21, and each of which has its other end portion 55 attached to the adjacent side rails 84 of the frame 51 (Fig. 2).

30 Extending between the side rails 84 of the frame 51 and transversely across the body 57 of the animal character 21 is a rod 58 (Fig. 2). This rod 58 projects through a slot 59 formed in a channel bar 60 which is arranged between the side rails 84 of the frame 51 (Fig. 8). This bar 60 is pivotally connected at its lower end, as at 61, to a link 62 which, in turn, is pivotally connected at its lower end, as at 63, to the supporting frame 43. The channel member 60 has marginal flanges 85 (Fig. 8) for a reason to be explained hereinafter.

35 The upright target, supporting member, or rod 23 is pivotally mounted at its lower end, as at 56, (Fig. 4) upon a vertically extending portion 70 of the supporting frame 43. Pivotally connected to the target-supporting member 23 between the ends of the latter, as at 64 (Fig. 4) is an arm 65. This arm 65 is pivotally connected at its upper end, as at 66 (Figs. 4, 5, and 15) to another arm 67 and the arm 67 is pivotally connected at its lower end, as at 68, to the supporting frame 43 (Fig. 4).

40 Pivotally mounted on the vertically extending portion 70 of the supporting frame 43 is a bracket 71 (Fig. 4) and pivotally connected at its lower end to the bracket 71, as at 72, (Figs. 2 and 4) is a latch operating arm 69, (Fig. 4); the arm 69

45 having at its upper end a laterally extending latch pin 73 (Figs. 3, 4, 5, 15, and 16). This latch pin 73 carries an anti-friction roller 95 thereon which rides upon the peripheral surface of a latch cam 74 which is mounted upon the shaft 46 at one end of the latter, (Fig. 2), the cam 74 50 having a notched portion 75 formed in its peripheral surface (Fig. 5).

Operation

55 The latch pin 73 is normally disposed in the notched portion 75 of the latching cam 74 (Figs. 4 and 5) and the latching cam 74, latch pin 73, and target 24 are normally disposed in the positions indicated in full lines in Fig. 4. In this 15 position of these parts, the engagement of the latch pin 73 in the notched portion 75 of the cam 74 prevents movement of the various parts of the new amusement apparatus, and the seat 27 is thereby latched in horizontal position so as 20 to support a boy thereon.

25 However, if and when a player succeeds in striking the target 24 with a ball or other missile, the impact of the missile against the target 24 pivots the target 24 and the target-supporting 25 member 23 (clockwise, from full to dotted line position, Fig. 4), and this movement of the target-supporting member 23 pivots the latch operating arm 65 upwardly (Fig. 4), thereby raising the other latch-operating arm 67, (from full to 30 dotted line position, Fig. 4), under the latch pin 73, thus lifting the latch pin 73 up out of the notched portion 75 of the latching cam 74.

35 The weight of the boy on the seat 27 then pivots the seat 27 downwardly, thereby dropping the boy off the seat 27 into the pool 20, and at the same time rotating the shaft 25 (counterclockwise, Fig. 9). This movement of the seat 27 and its supporting shaft 25 acts through the gears 36, 37 to rotate the vertical shaft 38 in the 40 channel or groove 39 (counterclockwise, Fig. 11) and this rotation of the vertical shaft 38 acts through the gears 40 and 41 to rotate the horizontal shaft 42 which in turn acts through the gears 44 and 45 to rotate the shaft 46 and the 45 latch cam 74 (clockwise, Figs. 4 and 5, from the position of Fig. 4 to the position of Fig. 5, the shaft 46 being thus rotated counterclockwise, Fig. 8). This rotation of the shaft 46 moves the animal character 21 upon its supporting structure 47-48-49-50-51-58-59-60-61-62 (counterclockwise, Fig. 8), thus imparting a swimming movement to the animal character 21 in the direction of the boy as the latter is dropped off the seat 27 into the pool 20. During this 55 movement of the animal character 21, the body portion 57 and the upper jaw portion 76 of the animal character 21 pivot downwardly upon the shaft 50, thus closing the upper jaw portion 76 of the animal character upon the lower jaw portion 52 of the same. During these movements of the animal character 21 the springs 53 keep the lower jaw portion 52 of the same in a substantially horizontal position and flush with the surface of the water in the pool 20. The extent or length of this movement of the animal character 21 is limited by the engagement of the upper end portion 86 of the link 62 with the marginal flanges 85 of the channel-shaped member 60 (Fig. 8).

60 The vertical side rails 77 of the ladder 28 are pivotally mounted at their upper ends on the shaft 42, by means of a bracket 78 (Figs. 8 and 13), and one of these side rails 77 of the ladder 28 is pivotally connected, at its lower end, as at 75

80, to a link 79 which, in turn, is pivotally suspended from the vertical post 22, as at 81 (Fig. 13).

When the seat 27 is in lowered or vertical position, the ladder 28 is in raised position (dotted line position, Figs. 8 and 13).

When the boy is dropped from the seat 27 into the pool 20 he emerges from the latter by climbing up the rungs 82 of the ladder 28 onto stationary 10 rung 93 which project laterally from the post 22 above the pool 20 (Fig. 8), and as he climbs up the ladder 28 his weight thereon pivots the latter 28 downwardly (from dotted to full line position, Figs. 8 and 13), thereby rotating the shaft 15 42 (clockwise, Fig. 13). This rotation of the shaft 42 acts through the train of shafts and gears 42—41—40—38—37—36—25 to rotate the shaft 25 (clockwise, Figs. 9 and 12), thus raising and resetting the seat 27—29 into horizontal position.

At the same time this rotation of the shaft 42 (clockwise, Fig. 13) acts through the gears 44—45 to rotate the shaft 46 (clockwise, Fig. 8), thereby 20 rotating the animal character 21 and its supporting structure 49—47—48—51—60, etc. (clockwise, Fig. 8), thus resetting the animal character 21 back into its initial position (Fig. 1); while at the same time this rotation of the shaft 46 (clockwise, Fig. 13) rotates the latch cam 74 carried thereby (counterclockwise, Figs. 4 and 5, from the position of Fig. 5 to the position of Fig. 4), thereby reengaging the latch pin 73 in the notched portion 75 of the latch cam 74, and thus 30 resetting the seat 27 in horizontal or raised position and the target 23—24, and animal character 21 in their initial positions.

Attached to and projecting laterally from the latch-operating arm 69 is a block 87 (Figs. 15 and 16) in which is provided a slot 88; the latch pin 40 73 being adjustable axially of this slot by means of set screws 89 and 90 which are mounted in the block 87 at opposite ends thereof.

The stroke or arc of movement of the target 24 and its supporting arm 23 (from full to dotted line position, Fig. 4) necessary to raise the latch pin 73 out of latching engagement with the notched portion 75 of the cam 74 to release the movable parts of the apparatus may be varied by adjusting the latch pin 73 axially of the slot 88 50 by means of the set screws 89 and 90.

The counterweighted arm 48 of the member 47 has a counterweight sleeve 94 slidably adjustable thereon by means of a pin and slot connection 91—92 (Figs. 8 and 14) and by adjusting the sleeve 91 axially along the arm 48 the weight of the animal character 21 and its supporting structure 49—51, etc., located above the frame 43 and shaft 46, may be properly balanced.

While I have illustrated and described the preferred form of construction for carrying my invention into effect, this is capable of variation and modification, without departing from the spirit of the invention. I, therefore, do not wish to be limited to the precised details of construction set forth, but desire to avail myself of such variations and modifications as come within the scope of the appended claims.

Having thus described my invention what I claim as new and desire to protect by Letters Patent is:

1. In an amusement apparatus, the combination of: a target; an animal character; a movably mounted supporting structure disposed above the said animal character and adapted to support an object thereon; means normally latching

5 said supporting structure in raised position against the force of gravity so as to support an object thereon; means actuated by a missile striking said target to release said latching means and said supporting structure so that the latter may drop by gravity and dislodge said object therefrom; and means actuated by the movement of said supporting structure to move said animal character in the direction of the said object, thus dislodged from said supporting structure. 10

2. In an amusement apparatus, the combination of: a target; an animal character; a movably mounted supporting seat disposed above the said animal character and adapted to support a man thereon; means normally latching the said seat in a raised, horizontal position against the force of gravity so as to support a man thereon; means actuated by a missile striking said target to release said latching means and seat so as to allow said seat to drop by gravity and dislodge 20 the man therefrom; and means actuated by the movement of said seat to move said animal character in the direction of the man thus dislodged from said seat.

3. In an amusement apparatus, the combination of: an upright target; an animal character; a pivotally mounted seat disposed above said animal character and adapted to support a man thereon; means normally latching said seat in a raised, horizontal position against the force of gravity so as to support a man thereon; means actuated by a missile striking said target to release said latching means so as to allow said seat to drop by gravity and dislodge the said man therefrom; and means actuated by the aforesaid 30 downward movement of said seat to move said animal character in the direction of the man thus dislodged from said seat.

4. In an amusement apparatus, the combination of: an upright target; an animal character; a pivotally mounted seat disposed above said animal character and adapted to support a man thereon; means normally latching said seat in a raised, horizontal position against the force of gravity so as to support a man thereon; means actuated by a missile striking said target to release said latching means so as to allow said seat to drop by gravity and dislodge the said man therefrom; and means actuated by the aforesaid 40 downward movement of said seat to move said animal character in the direction of the man thus dislodged from said seat; and means for resetting the aforementioned parts in their initial positions; said resetting means including a ladder by which the man dislodged from said seat 45 may climb up toward the latter.

5. In an amusement apparatus, the combination of: a target; an animal character; pivotally mounted means for supporting a man above the said animal character; means normally latching the said supporting means in position to support a man thereon against the attraction of gravity; means actuated by a missile striking said target to release said latching means from latching engagement with said supporting means so as to allow the said supporting means to drop by the attraction of gravity and dislodge the man therefrom; and means actuated by the said dislodging or dropping movement of said supporting means to move said animal character in the direction of the man thus dislodged from said supporting means. 60

6. In an amusement apparatus, the combination of: a target; an animal character; pivotally mounted means for supporting a man above the

said animal character; means normally latching the said supporting means in position to support a man thereon against the attraction of gravity; means actuated by a missile striking said target to release said latching means from latching engagement with said supporting means so as to allow the said supporting means to drop by the attraction of gravity and dislodge the man therefrom; means actuated by the said dislodging or dropping movement of said supporting means to move said animal character in the direction of the man thus dislodged from said supporting means; and means for resetting the aforementioned parts into their initial positions; said resetting means including a ladder by which the man dislodged from said supporting means may climb upwardly toward the same.

7. In an amusement apparatus, the combination of: a target; pivotally mounted means for supporting a man above said target against the attraction of gravity; means normally latching

the said supporting means in position to support a man thereon against the attraction of gravity; means actuated by a missile striking said target to release said latching means from latching engagement with said supporting means so as to allow the latter to drop by gravity and dislodge a man therefrom; and means actuated by the said dropping movement of said supporting means to move an object in the direction of the man dislodged from said supporting means.

8. In an amusement apparatus, the combination of: a target; pivotally mounted means for supporting an object above said target; means actuated by a missile striking said target and co-acting with said supporting means to dislodge said object from said supporting means; and means actuated by the said missile striking said target to move an object in the direction of the said first-named object thus dislodged from said supporting means.

PAUL F. GAUS.
